UNITED STATES PATENT OFFICE.

JOHN EDWARD CREWS, OF SUNLAND, CALIFORNIA, ASSIGNOR TO DAVID F. YOUNG-BLOOD, OF SAN ANTONIO, TEXAS.

RELIEF DEVICE FOR OIL TANKS.

Application filed March 23, 1923. Serial No. 627,192.

To all whom it may concern:

Be it known that I, JOHN E. CREWS, a citizen of the United States, residing at Sunland, in the county of Los Angeles and State of California, have invented new and useful Improvements in Relief Devices for Oil Tanks, of which the following is a specification.

My invention relates to an automatic relief device adapted to be installed upon the decks of tanks which are used for receiving and storing petroleum or derivatives of petroleum such as gasoline, kerosene, distillate or other volatile liquid.

15 The general object of the invention is to provide a device which normally forms a liquid seal for preventing the escape and dissipation of the volatile contents of the liquid contained in the tank, but which is provided 20 with means for relieving excess pressure or vacuum when the same becomes great enough to threaten injury to the tank. The invention is also provided with means for adjusting the amount of pressure which may be 25 reached within the tank before affording relief, whereby the device may be adapted to suit the strength of the tank to which it is to be applied. The sealing device also is 30 filled automatically when a certain level is reached within the tank, and after the device is once installed, no further attention is required.

The invention will be best understood from the following description considered in connection with the accompanying drawing which illustrates the preferred structure by means of which the invention may be carried out.

In the drawings:—

40 Fig. 1 is a vertical sectional view of a portion of a tank having my device installed thereon.

Fig. 2 is a similar view showing the liquid seal and pressure-releasing device in section.

45 Fig. 3 is a sectional view on the line 3—3 of Fig. 1.

Fig. 4 is a sectional view on the line 4—4 of Fig. 1.

Referring more specifically to the drawing, 50 the tank 5, which is adapted to contain oil or other volatile liquid, is provided, as usual, with a top wall or deck 6 on which the invention is mounted. The invention comprises a U-shaped pipe 7 having legs 8 and 9 secured 55 to the under side of the deck 6, by flanged

couplings 10 and 11 or other suitable means, the lower part of the pipe being adapted to contain sealing liquid 12 of the same character as the liquid contained in the tank. One leg, as 9, is provided with a series of internally threaded openings arranged one above the other, to one of which may be connected a nipple 13 and elbow 14 from which a comparatively small tube 15 extends downwardly to a point near the bottom of the 60 tank, preferably about eighteen inches from the bottom. The other openings may be provided with plugs 16, either one of which may at any time be removed to adjust the tube 15 and nipple 13.

It will be understood that the tube 15 provides restricted means of communication between the pipe 7 and the bottom portion of the tank, and that any excess of liquid within the pipe will eventually be discharged 65 through the tube 15 into the tank. Liquid may also be discharged from the tank into the pipe 7, whenever the level within the tank rises to a sufficient height. Thus, after the device is once installed, it ordinarily 70 requires no further attention. The leg 9 opens into a return bend 26 forming a continuation of the pipe and providing a free communication between the same and the upper portion of the tank. Whenever the 75 gases escaping from the liquid in the tank create a pressure, the liquid 12 is forced downwardly in the leg 9, and if the pressure becomes greater than the predetermined maximum, a portion of the gas is permitted to 80 escape through the liquid seal and leg 8 into the atmosphere. A dome 17 is secured to the upper surface of the deck 6 to receive any overflow of the liquid 12 which may be caused by the pressure in the leg 9, the dome 85 being provided with a port 18 through which the gases may escape until the pressure within the tank is relieved.

Whenever oil is pumped out of the tank, thus tending to create a vacuum, as soon as 100 the deficiency in pressure within the tank reaches a point liable to cause injury to the tank, the pressure of the atmosphere entering through the port 18 will cause the oil 12 to rise in the leg 9 until the leg 8 is emptied 105 and the atmosphere may enter through the pipe 7 and return bend 26 and relieve the vacuum condition.

The tube 15 provides a compensating device through which to gage the amount of 110

pressure or vacuum which may be reached before being relieved. The connection between the tube 15 and the leg 9 may be adjusted vertically by interchanging the same with one of the plugs 16. Thus, when the tube is connected with the lowermost hole, the maximum pressure or vacuum may be four ounces to the square inch, and when connected to one of the other openings, the maximum pressure or vacuum may be eight ounces or sixteen ounces to the square inch, respectively. It will, of course, be understood that the height of these openings above the horizontal portion of the pipe 7 will determine the amount of pressure to which the relief device is responsive and may be varied, as desired, and the tube 15 may be connected to any one of the openings to which the strength of the tank is adapted. The return bend 26 and dome 17, therefore, provide means for relieving excess vacuum or pressure within the tank, and at the same time retain sufficient liquid to restore the seal as soon as the abnormal condition is corrected. The tube 15 also provides means for regulating the pressure by permitting any excess oil to escape from the tube 7 and also permitting the tube to be automatically re-filled. A clean-out plug 19 is preferably provided in the bottom of the pipe 7, so that if the device becomes clogged by sediment of any kind, it may be immediately relieved by removing the plug and cleaning out the pipe. While I have shown and described specifically one form in which my invention may be embodied, it will be understood that this is merely illustrative and that the details of construction may be modified, and that the seal may be located in various positions either inside or outside the tank, without departing from the scope of the invention as claimed.

What is claimed is:—

45. 1. A receptacle for liquids comprising top, bottom and side walls, a pipe secured to the top wall and having a substantially U-shaped portion depending therefrom and adapted to contain liquid to form a seal, one end of the pipe being open to the atmosphere and the other end open to the interior of the receptacle, and a comparatively small tube communicating with the interior of one branch of the pipe below the end which is open to the interior of the receptacle and extending downwardly therefrom toward the bottom of the receptacle.
50. 2. A receptacle for liquids, comprising top, bottom and side walls, a substantially U-shaped pipe secured to the top wall and depending therefrom and adapted to contain liquid to form a seal, a plurality of holes tapped into one leg of the pipe at different levels, a comparatively small tube adapted
55. 65. to be secured in any one of said holes and

to extend to a point near the bottom of the receptacle, and plugs for the remaining holes.

3. A receptacle for liquids, comprising top, bottom and side walls, a substantially U-shaped pipe with each end secured to and opening through the top wall and depending therefrom, a return bend forming a continuation of one leg of the pipe and opening into the top of the receptacle, a comparatively small tube communicating with the interior of one leg of the pipe and extending downwardly toward the bottom of the receptacle.

4. A receptacle for liquids, comprising top, bottom and side walls, a substantially U-shaped pipe secured to the top wall and depending therefrom, a return bend forming a continuation of one leg of the pipe and opening into the top of the receptacle, one of said legs having a plurality of openings therein, a comparatively small tube selectively connected to one of said openings and extending to a point near the bottom of the tank, and plugs for closing the remaining openings.

5. A receptacle for liquids, comprising top, bottom and side walls, a substantially U-shaped pipe secured to the top wall and depending therefrom and adapted to contain liquid to form a seal, and means for adjustably limiting the height of said liquid, so as to adjust the amount of pressure under which the seal will be broken.

6. A receptacle for liquids comprising top, bottom and side walls, a substantially U-shaped pipe secured to the top wall and depending therefrom and adapted to contain liquid to form a seal, means above the top wall to retain the overflow from one leg of the pipe, and means below the end of the other leg for automatically filling the seal with liquid from the receptacle when the latter reaches a predetermined height.

7. The combination with a receptacle for liquids, of a substantially U-shaped pipe depending within the receptacle and having each leg secured to an opening through the wall of the upper part of the receptacle, one communicating with the atmosphere and the other continuing in a return bend which opens into the receptacle, and means for automatically introducing a portion of the liquid contents of the receptacle into the lower part of the U-shaped pipe to form a liquid seal when said liquid contents reaches a predetermined level below the top of the receptacle.

8. A liquid seal for receptacles containing liquids, comprising a substantially U-shaped pipe adapted to be secured to the under side of the top wall of the receptacle, adjustable means for establishing direct communication between one leg of the pipe and the bottom part of the receptacle, a return bend forming a continuation of one leg of

the pipe and adapted to communicate with the interior of the receptacle to permit relief of pressure therein, and an overflow receptacle connected with the other leg of the 5 pipe.

9. A liquid seal for receptacles containing liquids, comprising a substantially U-shaped pipe adapted to be secured to the underside of the top wall of the receptacle, a return 10 bend forming a continuation of one leg of the pipe and adapted to communicate with the interior of the receptacle to permit relief of pressure therein, and an overflow receptacle connected with the other leg of the 15 pipe and open to the atmosphere.

10. A liquid seal for receptacles, comprising a substantially U-shaped pipe adapted to be secured to the underside of the top 20 wall of the receptacle, and adjustable means for establishing direct communication between one leg of the pipe and the bottom part of the receptacle.

11. A receptacle for liquids comprising top, bottom and side walls, a substantially 25 U-shaped pipe secured to the top wall and depending therefrom, one leg of the pipe opening to the atmosphere, and a return bend forming a continuation of the other

leg of the pipe and opening into the top of the receptacle. 30

12. In combination with a receptacle for liquids, a pipe adapted to contain liquid to form a liquid seal for the receptacle, one end of the pipe being open to the atmosphere and the other end open to the interior of the 35 receptacle, and means for automatically introducing liquid into the pipe to form a seal when a certain level is reached within the receptacle, which level is below the end which is open to the interior of the receptacle. 40

13. A liquid seal for receptacles containing liquids, comprising means responsive to a predetermined excess of pressure inside the receptacle to permit the escape of gas therefrom into the atmosphere and responsive to a deficiency in pressure of a like amount to admit air from the atmosphere to the receptacle, and means for automatically introducing liquid from the receptacle to form the 45 seal when the liquid within the receptacle reaches a predetermined level. 50

In testimony that I claim the foregoing as my own, I have hereto affixed my signature.

JOHN EDWARD CREWS.
